MATCH PACKET

Ell E. Penter, Huntington Park, Calif.

Application March 1, 1943, Serial No. 477,518

3 Claims. (Cl. 206—29)

The present invention relates particularly to that type of safety matches commonly produced and used in what are known as match packets, wherein the match splints are parts of match combs secured in a folded cover, a portion of which constitutes an opening flap adapted, in the closed position, to cover the splints and their striking tips or heads.

Commonly, the covers of match packets of the above type, have portions embracing, and fixed to, the base portions of the combs at the lower ends of the match splints, one of the embracing portions of the cover having an external surface coating chemically constituted to cause ignition of the coated splint tips or heads by abrasion.

In the use of such packets the cover, after having been opened to permit of detachment of a splint, should be closed while the match is ignited, in order to avoid the danger of communication of ignition to the remaining splints, and though the match packets usually are imprinted with such instruction, it is, in many instances, overlooked through carelessness, and with painful and, in some instances, disastrous results.

It is plain, and well known, that the cover of the usual match packet serves a necessary and important safety purpose, in addition to the fact that it provides a surface for the imprinting of advertisements of various character.

It is one of the objects of the present invention to provide a match packet in which the splint striking surface or means is so constituted and arranged as to protect the undetached splints from danger of ignition during ignition of a detached splint, and to thus effectively eliminate such danger whether or not the cover is closed while abrasively igniting a splint, and indeed, whether or not a cover, as such, is present.

It is further well known that the splint combs of the common match packets are necessarily formed of heavy paper or paper board, even though wood splints are more economical and are superior in use by reason of their greater strength and adaptability to avoid flexure and fracture during striking, and their greater resistance to the weakening effect of moist air on the more hygroscopic paper. The reason for the common use of paper splints is the fact that in the present manufacture of match splints the comb blanks are first slit to form the splints, and then alternate splints are laterally bent or offset before passing through the heading chemical so as to separate the free ends of the splints whereby individual heads are formed and sufficient chemical is accumulated on each splint end to provide for quick and efficient ignition.

It is another object of the present invention to provide a method and means whereby the in-

dividual heading of the splints, in the first instance, is eliminated, so as to avoid a wedge-shaped packet, which is now the common result of lateral offsetting of the splints to provide individual heads, and also to do away with the usual step of laterally offsetting the splints, and to permit of the use of wood splints in the place of paper splints wherever it may be desirable for any reason to do this. The result of the present invention is a match packet which may be of the same thickness from end to end, in order to pack effectively without alternate reversal of the packets, and which may be safely used without the necessity of opening and closing a cover flap.

The best mode thus far devised for carrying the invention into practical effect is shown in the accompanying drawing, and will now be described in detail in reference thereto. In the drawing, which forms a part of this specification:

Figure 1 is a perspective view of a comb blank, which may be either paper or wood.

Figure 2 is a similar view of the blank after it has, during the next step of manufacture, passed through the heading chemical to form a thin, deep coating continuously along one edge portion thereof.

Figure 3 is another similar view, showing the next step which consists in partially slitting the blank to form the splints, the slits being extended through the coating applied in the previous step.

Figure 4 is another similar view of a complete match packet, embodying all of the essentials of safety according to the present invention, and including splints and splint combs produced in accordance with the present method.

Figure 5 is a perspective view showing the possible use of side cover members for printing and advertising matter.

Figure 6 is an enlarged vertical sectional view through the assembly of Figure 5, taken substantially on line 6—6 of said figure.

Figure 7 is a perspective view illustrating the manner of holding the packet of Figure 4 while striking a match splint.

Figure 8 is a similar view showing a modified and simplified packet, and

Figure 9 is an enlarged partial vertical sectional view taken substantially on line 9—9 of Figure 8.

Referring now to the above figures, and starting with a thin rectangular blank 10, as in Figure 1, which may be of either paper or wood, the method according to the present invention, proposes the passing of one edge portion of the blank 10 through a head forming chemical so as to form a coating of such material on said edge portion, as indicated at 11 in Figure 2. This step

is preferably regulated, as by governing the speed of the coating operation, and the consistency of the heading chemical, so that the coating is evenly thinly and uniformly along the sides of the blank adjacent the coated edge, and extends for a substantial distance from said edge to provide depth rather than thickness.

The next step in the present method is the slitting of the blank, as at 12 in Figure 3, the slits being extended through the coating, or rather through the coated edge 11, to a point short of the opposite edge of the blank, so that a comb 13 will be formed in which the splints 14 and their heads 15 will be in a single line and in the same plane with one another and with the base 16, or unslotted edge portion of the blank. Due to this, the splint heads will remain, until removed for striking, in sidewise or lateral abutting relation so as to mutually cooperate to avoid ready distortion of the comb. Furthermore, since there has been no offsetting of the splints to initially form individual heads, it is obvious a wood blank may be used which is thinner than would be necessary if formed of paper.

Having thus formed the combs, a two-comb packet, as indicated in Figure 4, may be assembled with the two combs 13 separated along their bases 16 by a separator strip 17, and with binding strips 18 along the outer portions of the bases 16. The binding strips 18, comb bases 16 and separator strip 17 may be glued, cemented or otherwise secured to one another as by means of a penetrating clip 19, and it is obvious that the thickness of the strips 17 and 18 may easily be such that the complete packet will be as thick at its base portion as at the splint heads. Thus the packets may be effectively boxed or packaged without alternate reversal, as with the usual wedge-shaped packets, and packing space, in this way, economized.

As a further and important feature of the invention, permitting the packet of Figure 4 to be complete without the necessity of a cover, it will be noted that the outer binding strips 18 have free edges lengthwise thereof, projecting beyond the confined corresponding edges of the comb bases 16 and the separator strip 17, as indicated at 20, so as to form between the extensions 20, a striking groove 21. Within this groove 21, the end surfaces of the combs 13 and separator strip 17, as well as the inner surfaces of the binding strip extensions 20, there is applied a coating, as at 22, of a chemical striking material against which the head of a detached splint may be ignited by friction as it is drawn lengthwise of, and within, the groove. The igniting head will, at the same time, be so isolated with respect to the remaining undetached splints of the combs of the packet, that the latter will be protected from danger of accidental ignition, since the groove 21 opens away from the headed ends of the undetached splints.

Further effective protection may be afforded by holding the packet with its undetached splints covered in the hand as in Figure 7, and with the striking groove 21 uppermost in convenient position for striking a detached splint, but this is merely an extra precaution, and is not by any means an essential as that of the closing of the cover flap of an ordinary match packet.

If it is desirable, for advertising or other printed matter, the binding strips 18 of the comb assembly of Figure 4, may be replaced by side cover members 23, as in Figures 5 and 6, such

members completely covering the outer sides of the combs. However, in the event such cover members are used, it is only for advertising or like purposes, since the protection afforded by the striking groove 21 substantially eliminates any necessity for further protection of the undetached splints.

It is also possible, as seen in Figures 8 and 9, to do away with the binding strips 18 of Figure 10 4, by so connecting the bases 16^a of the combs 16^a, to the separator strip 17^a, that their lower edges project below the separator strip and form extensions 24. By chamfering the inner surfaces of the extensions 24, a tapering striking groove 21^a is formed, the lower edge of the separator strip and the inner surfaces of the chamfered extensions being coated with a striking chemical, as seen at 25. This form of the invention presents a packet of utmost simplicity, stripped of non-essentials, and well adapted to serve any purpose for which a safety match packet is ordinarily used, except that of advertising. Even in the latter respect, matter printed directly on the blank of each comb may well serve for limited advertising.

The method and construction thus shown and described offers great advantages in practical use, not only in the manufacture of the match packets, and the combs thereof, but in effectiveness 30 as regards certain and safe ignition in use and convenience and economy not only in packaging for sale, but convenience of the substantially uniformly flat packet when carried in the pocket or purse.

Having thus fully disclosed the invention, what is claimed is:

1. A match packet, consisting of a pair of parallel splint combs including opposingly connected base portions, each having a series of upstanding 40 splints with striking heads at their upper free ends remote from said base portions, the said base portions having chamfered lower facing edges forming a groove between and along the same, and a friction striking material on one or 45 more of the chamfered surfaces or walls of said groove.

2. A match packet comprising a pair of opposing, substantially parallel splint combs, each comb including a base portion in a single piece, 50 and a series of splints upstanding from said base portion and having upper striking heads, the splints and heads of each comb being respectively aligned, and a separator strip disposed between and rigidly connected to, said base portions, with 55 its lower edge in vertically spaced, substantially parallel relation above the lower edges of said base portions, to thus form with the latter edges a groove along the bottom of the packet, of the width of said strip, opening away from the splint heads, and a friction igniting material on one or 60 more of the walls of said groove.

3. A match packet comprising a pair of opposing splint combs, each comb comprising a base portion in a single piece and a series of splints 65 upstanding from said base portion and having upper striking heads, a separator strip disposed between, and connected to, said base portions of the combs, the said base portions having their lower edges projecting beyond the separator strip 70 and provided with chamfered inner surfaces forming, with the said strip, a substantially V-shaped groove, and a friction igniting material on one or more of the walls of said groove.
